(57) **CLAIM**

The ornamental design for a display screen with graphical user interface, as shown and described.

DESCRIPTION

FIG. 1 is a front view of a display screen showing a first image of a graphical user interface;

FIG. 2 is a front view of a display screen showing a second image of the graphical user interface;

FIG. 3 is a front view of a display screen showing a third image of the graphical user interface;

FIG. 4 is a front view of a display screen showing a fourth image of the graphical user interface;

FIG. 5 is a front view of a display screen showing a fifth image of the graphical user interface;

FIG. 6 is a front view of a display screen showing a sixth image of the graphical user interface;

FIG. 7 is a front view of a display screen showing a seventh image of the graphical user interface;

FIG. 8 is a front view of a display screen showing an eighth image of the graphical user interface; and,

FIG. 9 is a front view of a display screen showing a ninth image of the graphical user interface.

The appearance of the graphical user interface of the display screen transitions between the images shown in FIGS. 1-9. The process or period in which the graphical user interface transitions forms no part of the claimed design. The long dash short dash broken lines illustrate the display screen and form no part of the claimed design. The remaining broken lines illustrate portions of the graphical user interface that form no part of the claimed design.

FIG. 5

FIG. 6

FIG. 7

FIG. 8

The image shows a smartphone screen displaying a mobile application for plant health management. The app interface includes a header with the date 'October 18, 2022' and a title 'Rust Disease' with a timestamp '9:41 AM'. Below the header is a photograph of a plant with visible rust symptoms. The main content area is divided into sections: 'Disease info' and 'Revive Plan'. The 'Revive Plan' section is active, showing 'Your present solutions' with two numbered steps: 1. Wipe or flush bugs from plants: Rub off mealybugs using a washcloth or your fingers. Use a hose to spray these pests off of your plants. Close examination of the plant on a regular basis is the best weapon against infestation. 2. Spray plants with insecticidal soap: Spray entire plant with insecticidal soap or neem oil. Avoid spraying on sunny days and make sure to make contact with the Mealybugs. The 'Updates' section shows a timestamp 'Time: October 19, 2021' and a status 'Result: Very good! The condition of your plant is getting better.' with three small thumbnail images of the plant. The 'Treatment expectations' section states 'Plants no longer show new symptoms of dry edges'. At the bottom is a button 'Ask Expert for Help'.

Rust Disease
